UNITED STATES PATENT OFFICE.

FRANK DENNISON PHINNEY, OF RANGOON, BURMA, ASSIGNOR TO LINOTYPE AND MACHINERY LIMITED, OF LONDON, ENGLAND.

DESIGN FOR A FONT OF BURMESE TYPE.

52,922.

Specification for Design.

Patented Jan. 28, 1919.

Application filed December 11, 1916. Serial No. 136,340. Term of patent 14 years.

To all whom it may concern:

Be it known that I, FRANK DENNISON PHINNEY, a citizen of the United States, residing at 70 Merchant street, Rangoon, Burma, have invented a new, original, and ornamental Design for a Font of Burmese Type, of which the following is a specification, reference being had to the accompanying drawing, forming part thereof.

The drawing is a representation of a font of Burmese type.

I claim:—

The ornamental design for a font of Burmese type as shown.

FRANK DENNISON PHINNEY.

Witnesses:

JAMES LUCAS SNYDER,
SAMUEL EMANUEL MINER.
